(57) **CLAIM**

The ornamental design for an adjustable bracket, as shown and described.

DESCRIPTION

FIG. 1 is a top perspective view of an adjustable bracket showing my new design.

FIG. 2 is a side view of the top view of the adjustable bracket of FIG. 1; the opposite side view of the adjustable bracket of FIG. 1 is the mirror image of FIG. 2.

FIG. 3 is a top view of the adjustable bracket of FIG. 1.

FIG. 4 is a bottom view of the adjustable bracket of FIG. 1.

FIG. 5 is a front view of the adjustable bracket of FIG. 1.

FIG. 6 is a rear view of the adjustable bracket of FIG. 1; and, FIG. 7 is a bottom perspective view of the adjustable bracket of FIG. 1.

The broken line showing of a partial pole is for illustrative purposes only and forms no part of the claimed design.
